UNITED STATES PATENT OFFICE

2,594,649

DUAL MANOMETER

James V. Hodshire, Oklahoma City, Okla.

Application March 16, 1948, Serial No. 15,133

2 Claims. (Cl. 73—401)

1

This invention relates to a dual manometer. It is an object of the present invention to provide two manometers on a single support and a common valve stem extending between the branches of the manometers for permitting the same to be closed as when the manometer is to be transported, the valve stem being in a head from which the branches of the manometer tubes extend and to which test connections can be fitted.

Other objects of the present invention are to provide a dual manometer which is of simple construction, inexpensive to manufacture, convenient to use and connect with portions of apparatus to be measured for pressure or vacuum, has minimum parts and efficient in operation.

For other objects and for a better understanding of the invention, reference may be had to the following detailed description taken in connection with the accompanying drawing, in which

Fig. 1 is a front elevational view of the manometer embodying the features of the present invention.

Fig. 2 is a side elevational view.

Fig. 3 is an enlarged fragmentary elevational view with portions broken away and shown in section.

Figs. 4 and 5 are respectively transverse sectional views taken on lines 4—4 and 5—5 of Fig. 3.

Referring now to the figures, 10 represents a support formed of plastic or other material on the upper end of which there is disposed an enlargement 11 into which extends a valve stem 12 of tapered formation. Extending vertically through the enlargement 11 are a plurality of vertical passages 13 having large end sections 14 and 15. The end sections 14 of the passages receive the upper ends of U-shaped tubes 16 and 17. The tube 17 lies within the U-shaped tube 16 and between its vertical portions there extends a measuring scale 18 on which pressure readings can be made. Test connections can be made with the threaded sections 15. The valve stem 12 is extended through a transverse opening 19 which traverses the vertical passages 13. The valve stem has holes 21 adapted to be aligned with the passages 13 or to be turned out of alignment therewith as the valve stem is turned to a closed position. Within the stem 12 and extending diametrically thereacross is a hole 24 into which can be extended a turning handle. The tubes 16 and 17 are fitted tightly within the large sections 14 of the passages 13 so as to be suspended therefrom free of outer means of support upon the supporting board 10. The supporting board 10 has a flange 26 extending around it to give protection to the tubes 16 and 17.

2

The manometer parts are preferably made of plastic, but where temperatures are high, the same may be constructed of aluminum and with the tubes formed of glass. Mercury may be carried in the tube 16 while in the tube 17 there can be carried the water.

While various changes may be made in the detail construction, it shall be understood that such changes shall be within the spirit and scope of the present invention as defined by the appended claims.

I claim:

1. In a dual manometer, a support provided with an enlargement on its upper end, inner and outer U-shaped manometer tubes having their upper ends extending into said enlargement, there being spaced parallel vertical passages extending through said enlargement and communicating with the ends of the manometer tubes, there being a transverse opening traversing the vertically extending passages, a tapered valve stem rotatably positioned in said transverse opening and having openings therein adapted to be aligned with the vertical passages, and a measuring scale

20 portion extending longitudinally of the support and positioned between the vertically extending portion of the inner tube.

2. In a dual manometer, a support provided with an enlargement on its upper end, a pair of 25 U-shaped manometer tubes having their upper ends extending into said enlargement, there being spaced parallel vertical passages extending through said enlargement and communicating with the ends of the manometer tubes, there being a transverse opening traversing the vertically extending passages, a tapered valve stem rotatably positioned in said transverse opening and having openings therein adapted to be aligned with the vertical passages, and a measuring scale

30 portion extending longitudinally of the support and positioned between the vertically extending portion of the innermost tube, one of said tubes being nested within the other of said tubes, and a flange projecting from said support for protecting said tubes.

35 3. In a dual manometer, a support provided with an enlargement on its upper end, a pair of U-shaped manometer tubes having their upper ends extending into said enlargement, there being spaced parallel vertical passages extending through said enlargement and communicating with the ends of the manometer tubes, there being a transverse opening traversing the vertically extending passages, a tapered valve stem rotatably positioned in said transverse opening and having openings therein adapted to be aligned with the vertical passages, and a measuring scale

40 4. In a dual manometer, a support provided with an enlargement on its upper end, a pair of U-shaped manometer tubes having their upper ends extending into said enlargement, there being spaced parallel vertical passages extending through said enlargement and communicating with the ends of the manometer tubes, there being a transverse opening traversing the vertically extending passages, a tapered valve stem rotatably positioned in said transverse opening and having openings therein adapted to be aligned with the vertical passages, and a measuring scale

45 portion extending longitudinally of the support and positioned between the vertically extending portion of the innermost tube, one of said tubes being nested within the other of said tubes, and a flange projecting from said support for protecting said tubes.

JAMES V. HODSHIRE.
